UNITED STATES PATENT OFFICE.

HERMENEGILD P. RAVENELLE, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

PROCESS OF PRODUCING OPHTHALMIC MOUNTINGS.

Application filed March 9, 1922. Serial No. 542,403.

To all whom it may concern:

Be it known that I, HERMENEGILD P. RAVENELLE, a citizen of the United States, residing at Southbridge, in the county of 5 Worcester and State of Massachusetts, have invented certain new and useful Improvements in Processes of Producing Ophthalmic Mountings, of which the following is a specification.

10 This invention relates to improvements in process of producing ophthalmic mountings, and has particular reference to such mountings which are constructed of a combination of metallic and non-metallic materials.

15 One of the principal objects of the present invention is the provision of a novel process of construction of mounting in which the two parts may be satisfactorily united without the use of supplemental 20 fastening devices, and in which the inherent resiliency of the non-metallic material will serve to retain it in place.

25 A further object of the present invention is the provision of a process of construction of this type in which either plain colored or mottled material may be employed, as desired, in place of its being possible to construct the mountings only from plain colored material as has been the case in the 30 past.

35 Other objects and advantages of my improved process should be readily apparent by reference to the following description taken in connection with the accompanying drawings, and it will be seen that I may make any modifications in the specific details of construction shown and described within the scope of the appended claims 40 without departing from or exceeding the spirit of my invention.

Figure I is a perspective view of the blank from which a rim member, or the like, is to be formed.

45 Figure II illustrates one step in the formation thereof.

Figure III is a cross sectional view illustrating a further step.

Figure IV is a cross sectional view of the completed construction.

50 Figure V is a view of the mill or cutter for performing the first step in the operation.

Figure VI is a similar view of another cutter employed by me.

Figure VII is a semi-diagrammatic view 55 illustrating the curling of the prepared stock.

Figure VIII is a view of the stock at the completion of this operation.

Figure IX is a view of the complete 60 mounting.

Prior to my invention I am aware that ophthalmic frames have been constructed having an inner metallic portion and an enclosing non-metallic portion. In the case 65 of frames having but a thin separate covering of non-metallic material they have been constructed either by bending up the non-metallic material from sheet form or by splitting an extruded tube. In the one case the inherent tendency of the material is to straighten out and become loosened, while in the other case it has been impossible to form the tube of anything but solid colored material. In addition tubular 70 stock possesses certain disadvantages in the matter of working, and the like, and stability, which it is unnecessary to enter into here.

It is the purpose of my invention, therefore, to provide a manner of producing 80 composition rims from either rod or sheet stock taking a blank as shown in Figure I, this being formed from the composition material 1 and being of round, square or other cross section, as desired. I then proceed to work up the blank as through the use of the cutter 2 forming the central groove or channel 3 with the adjacent bevel edges 4, as is clearly illustrated in Figure 85 II.

II. The stock having been thus formed I make use of the supplemental cutter 5 having the neck 6 fitting into the upper portion of the groove 3, the cutter 5 serving to enlarge the groove 3 into the circular shape 90 as indicated at 7. The blank will then be found to have the substantially feathered edges at the point 8 and to be otherwise of generally uniform thickness and strength 95 having any desired markings, and of the proper strength, coherence, and the like, to produce most satisfactory results. The same having been grooved, I then pass it between the rollers 9 and 10, the roller 10 100 engaging the bevel portion 4 and crimping the same somewhat inward, thus lessening the diameter of the stock at that side so that it comes out in the substantially 105

spirally curved member shown in Figure VIII. The rolls 9 and 10 are so designed that this spiral will be slightly smaller than the normal diameter of the metal lens receiving frame 11 so that when the member 1 is sprung therearound, as indicated in Figures IV and IX, it will firmly remain in place held by its inherent resiliency, and there will be no tendency of the same to become disengaged through the action of heat or other influence.

I claim:

1. The process of forming a non-metallic covering for a metal frame, consisting in primarily producing a composition member in bar form, longitudinally slotting said bar, beveling the walls of the slot, subsequently interiorly milling the walls of the slot to produce a member of substantially split tubular form, substantially as illustrated.

2. The process of forming a non-metallic covering for a metal frame, consisting in primarily producing a composition member in bar form, longitudinally slotting said bar, beveling the walls of the slot, subsequently interiorly milling the walls of the slot to produce a member of substantially split tubular form, and rolling the material after

milling whereby the slotted side will be compressed to cause the member to assume a curled form.

3. The process of forming a non-metallic covering for a metal frame, consisting in primarily producing a composition member in bar form, longitudinally slotting said bar, beveling the walls of the slot, subsequently interiorly milling the walls of the slot to produce a member of substantially split tubular form, rolling the material after milling whereby the slotted side will be compressed to cause the member to assume a curled form, and snapping the curled member over a metal frame.

4. The process of forming a composition covering for a metal frame, consisting in slotting a bar of composition material with a cutting member having a slot forming portion and an edge beveling portion, and subsequently removing portions of the walls of the slot through the use of a ball end mill, substantially as illustrated.

In testimony whereof I have affixed my signature, in presence of two witnesses.

HERMENEGILD P. RAVENELLE.
